(57) **CLAIM**

The ornamental design for a dental syringe, as shown and described.

DESCRIPTION

FIG. 1 is a front left perspective view of a dental syringe according to the present invention.

FIG. 2 is a front right perspective view of the dental syringe of FIG. 1.

FIG. 3 is a bottom right perspective view of the dental syringe of FIG. 1.

FIG. 4 is a bottom left perspective view of the dental syringe of FIG. 1.

FIG. 5 is a right side view of the dental syringe of FIG. 1.

FIG. 6 is a front view of the dental syringe of FIG. 1.

FIG. 7 is a left side view of the dental syringe of FIG. 1.

FIG. 8 is a rear view of the dental syringe of FIG. 1.

FIG. 9 is a top view of the dental syringe of FIG. 1.

FIG. 10 is a bottom view of the dental syringe of FIG. 1.

FIG. 11 is an open left perspective exploded view of the dental syringe of FIG. 1.

FIG. 12 is an open right perspective exploded view of the dental syringe of FIG. 1.

FIG. 13 is an open bottom left perspective exploded view of the dental syringe of FIG. 1.

FIG. 14 is an open bottom right perspective exploded view of the dental syringe of FIG. 1.

FIG. 15 is an open left side exploded view of the dental syringe of FIG. 1; and,

FIG. 16 is an open right side exploded view of the dental syringe of FIG. 1.

The broken lines in the drawings illustrate portions of the dental syringe and form no part of the claimed design.

1 Claim, 16 Drawing Sheets
